Primary Examiner — Mitchell I. Siegel(74) *Attorney, Agent, or Firm* — Finnegan, Henderson, Farabow, Garrett & Dunner, L.L.P.(57) **CLAIM**

The ornamental design for a water ride, as shown and described.

DESCRIPTION

FIG. 1 is a perspective view of a water ride showing an embodiment of our new design;

FIG. 2 is a top view thereof;

FIG. 3 is a bottom view thereof;

FIG. 4 is a left side view thereof;

FIG. 5 is a right side view thereof;

FIG. 6 is an end view thereof;

FIG. 7 is an opposite end view thereof;

FIG. 8 is a perspective view of a water ride showing another embodiment of our new design;

FIG. 9 is a top view thereof;

FIG. 10 is a bottom view thereof;

FIG. 11 is a left side view thereof;

FIG. 12 is a right side view thereof;

FIG. 13 is an end view thereof; and,

FIG. 14 is an opposite end view thereof.

The broken line showing of the water ride is included for the purpose of illustrating unclaimed subject matter and forms no part of the claimed design.
